United States Patent Office

Des. 208,336

Patented Aug. 15, 1967

208,336

REPRODUCTION APPARATUS

John J. Van Acker, Chesterland, Ohio, assignor to Addressograph-Multigraph Corporation, Mount Prospect, Ill., a corporation of Delaware

Filed Oct. 1, 1965, Ser. No. 87,280

Term of patent 14 years

(Cl. D61—1)

Fig. 3.

Fig. 4.

FIG. 1 is a perspective view of a reproduction apparatus, showing my new design;

FIG. 2 is an elevational view of the side opposite that shown in FIG. 1;

FIG. 3 is a rear elevational view thereof; and

FIG. 4 is a top plan view thereof.

I claim:

The ornamental design for a reproduction apparatus, substantially as shown.
